WATER CRAFT

Woodrow Friddell, Chattanooga, Tenn.

Application February 5, 1957, Serial No. 44,759

Term of patent 14 years

(Cl. D71—1)

The single figure is a perspective view of the water craft, showing my new design.

The opposite side of the water craft is substantially the same in appearance as the side shown.

I claim:

The ornamental design for a water craft, as shown and described.
